HENRY JACKSON, OF NEW YORK, N. Y.

Letters Patent No. 72,499, dated December 24, 1867.

IMPROVEMENT IN DOOR-LOCKS.

The Schedule referred to in these Letters Patent and making part of the same.

TO ALL WHOM IT MAY CONCERN:

Be it known that I, H. JACKSON, of the city, county, and State of New York, have invented a new and improved Lock; and I do hereby declare that the following is a full, clear, and exact description thereof, which will enable others skilled in the art to make and use the same, reference being had to the accompanying drawings, forming part of this specification.

This invention consists of an expanding stump arranged in relation with tumblers, and a slide-bolt of peculiar construction, as hereinafter fully shown and described, whereby a greater security than hitherto is obtained against the picking of the lock; and the invention further consists in corrugating or notching one edge of the tumblers, and having a pin on a slide to engage with the notches and prevent the tumblers being moved or tampered with by a pick when brought in contact with the stump, which arrangement also serves as a safeguard against picking. In the accompanying sheet of drawings—

Figure 1 represents an internal view of the lock in a locked state, with the tumblers in a loose state, or acted upon only by their springs.

Figure 2, an internal view of the same, with the tumblers acted upon by the key, so that their slots will all be in line with each other.

Figure 3, an internal view of the same, with the tumblers removed and the stump in an expanded state.

Figure 4 are internal views of the same, with the tumblers removed and the stump contracted, in order that the slots in the tumblers may receive it.

Similar letters of reference indicate corresponding parts.

A represents the case of the lock, constructed in the usual or in any proper manner, and B is the bolt, which is constructed of two parts, *a b*, the part *a* being the bolt proper, and the part *b* a slide, which is not connected to the bolt proper or part *a* in a direct manner, but through the intervention of the tumblers. Figs. 3 and 4 show the parts *a b* of the bolt plainly. C represents a stump, which is composed of two parts, *c c'*, working on one and the same pivot, *d*. These parts are kept distended or separated by springs *e*. D represents a series of tumblers, any proper number being used. These tumblers are all fitted on one and the same pin, *f*, which is attached to the part *a* of the bolt proper, and each tumbler has a spring, *g'*, attached, which springs have a tendency to keep the ends of the tumblers against a stop, *h*, as shown in figs. 1 and 2. The tumblers D are all slotted, as shown at *i*, at different points, so as to require the different tumblers to be moved at different distances in order to bring the several slots *i* in line with each other, in order that the slots *i* may receive the stump C and admit of the tumblers D being shoved back, and with them the bolt B. The slide part *b* of the bolt B has a pin, *j*, projecting from it, which bears against the inner edges of the tumblers and moves said tumblers back when the key acts against the slide *b*, the tumblers forming the connection between *a* and *b*, as before stated. The bits of the key are so formed that in turning the key to unlock the lock, the tumblers D are first moved to bring the several slots *i* all in line with each other to receive the stump, the key, after the tumblers are thus adjusted, then acting against slide *b* and forcing the tumblers back, and with them the part *a* of the bolt proper.

In order, however, that this may be accomplished, the stump C must be compressed or contracted, as the springs *e* keep the parts *c c'* distended, so that the slots *i* are too narrow to receive it. This compressing of the stump is effected by the slide *b*, the end of which near the stump has a slot, *k*, made in it, having a V-shaped outer edge, so that when the slide *b* is moved toward the stump, under the action of the key, the bevelled edge of the notch will act upon the ends of the parts *c c'* of the stump and compress the same together so that the slots *i* of the tumblers can receive the stump, the stump of course being compressed just previous to the slots *i* reaching it. This serves as a great safeguard against picking, as it completely baffles the obtaining of a pressure of the tumblers against the stump with a view of ascertaining the position of the slots in the tumblers. Besides this safeguard, the pin *j* of the slide *b* is also made to perform a like office, as the edges of the tumblers against which it bears are notched or slotted, as shown at *l*, and when the slide *b* is forced back under the action of the key to move the tumblers back, the pin *j* catches into one of the notches of each tumbler and locks the same, so that they cannot be moved or turned on their pin *f* at all. Hence all tampering with the tumblers in order to obtain a pressure on the stump is avoided.

The springs *g* of the tumblers are formed with heads *m* on their inner ends, to fit in holes *n* in the tumblers at the inner ends of the slots *o*, as shown in figs. 1 and 2.

By this arrangement the springs are prevented from being casually drawn out from the tumblers. The stop pin *h* is important, as it limits the throw of the tumblers under the action of their springs *g*, and insures a proper position of the tumblers each time the key is made to act upon them to unlock the lock.

Having thus described my invention, what I claim as new, and desire to secure by Letters Patent, is—

1. The bolt *B*, composed of the two parts *a* *b*, the former, *a*, having the tumblers *D* attached, and the latter, *b*, provided with the pin *j*, to act against the tumblers in order to force them back, and with them the bolt, substantially as shown and described.

2. The notches at the edges of the tumblers *D*, against which the pin *j* bears, in order to lock the tumblers after their slots *i* have been adjusted in line with the stump *C*, substantially as shown and described.

3. The expanding stump *C*, in combination with the slide *b* of the bolt, provided with the slot *k*, for compressing the stump in order that the slots *i* may receive it, substantially as set forth.

The above specification of my invention signed by me, this fourteenth day of October, 1867.

HENRY JACKSON.
